United States Patent Office.

CALVIN BIRD, OF DORCHESTER, MASSACHUSETTS.

Letters Patent No. 70,789, dated November 12, 1867.

IMPROVED BARREL-COVER.

The Schedule referred to in these Letters Patent and making part of the same.

TO ALL WHOM IT MAY CONCERN:

Be it known that I, CALVIN BIRD, of Dorchester, in the county of Norfolk, and State of Massachusetts, have invented a new and useful Improvement in the Construction and Manufacture of Barrel-Covers for use in families, grocery stores, and other similar situations; and I do hereby declare that the following is a full, clear, and exact description thereof, reference being had to the accompanying drawings, and to the letters of reference marked thereon.

In portable barrel-covers, as heretofore constructed, the handle has generally been formed by cutting a slot for the fingers in a projecting cleat on top of the barrel-cover, extending entirely or partially across the same; and as barrel-covers are generally constructed of two or more pieces of boards, this cleat fastens and contributes to the strength of the cover; but inasmuch as it projects above the smooth surface of the cover, it is inconvenient in families, grocery stores, and other places where it would oftentimes be a great convenience to have the barrel-covers flush and smooth on top, so that other articles might be readily placed on the same. My improvement obviates these objections. In the drawings—

Figure 1 is a top view.

Figure 2 is an under side view.

Figure 3 is a cross-section on line A B of figs. 1 and 2.

a represents the barrel-cover proper, *b* the rim or flange. In the centre of the cover, I make an opening of four or five inches in diameter. I then apply a metallic cleat, *c*, secured to the under side of the barrel-cover, whereby it strengthens the cover as effectually as the ordinary cleat on top. This metallic cleat, as shown by the drawing, is bent upward at *d* in the central aperture, and comes flush with the top of the same, and forms the flush handle. I then cover the central aperture underneath with a metallic guard-plate, *e*, the periphery of the same being tacked to the under side of the barrel-cover. This plate I ordinarily make somewhat convex, as shown by the drawing, in order to gain some more space than the mere thickness of the board of the cover for the fingers when taking hold of the flush handle.

I do not confine my claim to the precise details of construction above recited, which, it is evident, may be varied in many ways without departing from the distinguishing features of my improvement; as, for instance, the handle, guard-plate, and strengthening-cleat may be formed of a single piece of cast metal, or other materials than metal may be used for the several parts; but I claim, as an improvement in the construction of barrel-covers—

The combination of the flush handle with the strengthening-cleat and guard-plate, substantially as described.

CALVIN BIRD.
